UNITED STATES PATENT OFFICE.

ORA A. COLBY, OF IRWIN, AND CHRISTIAN AALBORG, OF PITTSBURGH, PENNSYLVANIA, ASSIGNORS TO WESTINGHOUSE ELECTRIC & MANUFACTURING COMPANY, A CORPORATION OF PENNSYLVANIA.

TOASTER-TRAY BUTTON.

Application filed May 9, 1923. Serial No. 637,751.

To all whom it may concern:

Be it known that we, ORA A. COLBY, a citizen of the United States, and a resident of Irwin, in the county of Westmoreland and State of Pennsylvania, and CHRISTIAN AALBORG, a citizen of the United States, and a resident of Pittsburgh, in the county of Allegheny and State of Pennsylvania, have invented a new and useful Improvement in

10 Toaster-Tray Buttons, of which the following is a specification.

Our invention relates to electric table toasters and particularly to means for actuating the trays of such toasters.

15 The object of our invention is to provide a relatively simple, inexpensive and easily manufactured tray button and tray-actuating means.

In practicing our invention, we provide a 20 toaster having sheet metal side members and a tray pivotally supported thereby. A member of substantially U-shape, has one of its ends secured to the side of the tray at its pivot and has an operating button secured to the other end thereof. The intermediate part of the member of U-shape is located outside of the frame and co-operates therewith to limit the turning movement of the tray in its downward direction.

30 In the single sheet of drawings,

Figure 1 is a view, in side elevation, of a portion of an electric table toaster comprising the device embodying our invention.

35 Fig. 2 is a view, in end elevation, of a portion of a toaster comprising the device embodying our invention.

40 Fig. 3 is a view, in side elevation, of a member of U-shape comprising a part of the device embodying our invention,

Fig. 4 is a view, in end elevation, of the member illustrated in Fig. 3, and

45 Fig. 5 is a view in end elevation of a tray button.

An electric toaster 11 comprises a suitable base 12 of relatively thin sheet metal having a plurality of heat insulating supporting members 13 suitably secured between the end portions of integral depending flanges 14. A pair of spaced, vertically-extending, sheet metal side members 15 are secured to the top portion of the base 12 and support a plurality of trays 16 therebetween. The

trays 16 are pivotally mounted in integral lateral extensions 17 of the respective side frames 15.

A heating element for the toaster comprises a pair of vertically-extending sheets 18 of a suitable electric insulating material, such as mica, located on the top of the base 12 and held thereon by any suitable means and supporting a resistor wire (not shown).

As this application is closely related to a companion application, Serial No. 630,271, filed on April 8, 1923, by O. A. Colby and assigned to the Westinghouse Electric & Manufacturing Company it is believed that further description of parts other than those relating directly to our invention is unnecessary, and reference may be had to the hereinbefore mentioned application for the other details of the device.

A member 19, of substantially U-shape, is provided with extended integral end portions 21 and 22, the end portion 21 having rounded ends and the end portion 22 being of substantially triangular form, as may be noted more particularly by reference to Fig. 4 of the drawing.

The rounded end 22 of the member 19 is provided with a plurality of spaced openings, the outer ones of which have rivet members 23 extending therethrough to secure the end 21 against the side portion of the tray 16. The intermediate opening in the end 21 is provided with a suitable lug 24 which is located in an opening in the portion 17 of the side frame 15 to provide a pivot upon which the tray 16 may swing. The outer end portion 22 of the member 19 is located within a tray knob or button 25 having a depression of hexagonal contour in its inner face into which the end 22 may fit and interlock therewith. A securing means, such as a rivet member 26, is employed to secure the button 25 on the end 22.

The tray 16 has two limiting positions relatively to the side frames 15, namely a substantially vertical one at which time a slice of bread placed therein is located closely adjacent to the heating element hereinbefore described to effect a toasting thereof, and a suitable horizontal position.

When the toasting of one side of a slice of bread has been completed, the operator grasps the knob 25 and effects a turning

movement thereof and of the tray 16 in an outwardly and downwardly direction and the downward movement of the tray is continued until the intermediate portion of the member 19 strikes the lower surface of the extensions 17 of the side frames 15, substantially as indicated in Fig. 2 of the drawing, whereby a stop is provided against further downward movement of the trays. As 10 two knobs are provided, the operator may effect the reciprocal turning movements from either side of the device.

The device embodying our invention comprises relatively few parts that are easily manufactured and assembled and that operate in a positive manner to effect the desired results.

Various modifications and changes in detail may be made without departing from 20 the spirit and scope of the invention and such modifications are intended to be covered by the appended claims.

We claim as our invention:

1. In a vertical toaster, in combination, 25 a frame comprising stationary side members having relatively narrow, integral, projecting portions, a material-supporting member supported by said projecting portions and having a turning movement relatively thereto, and a member of substantially U-shape secured to said material-supporting member for turning the same.

2. In a vertical toaster, in combination, 35 a frame comprising stationary side members having relatively narrow, integral, projecting portions, a material-supporting member supported by said projecting portions and having a turning movement relatively thereto, and a member of substantially U- 40 shape secured to said material-supporting member for turning the same, and for limiting the turning movement in one direction.

3. In a vertical toaster, in combination, 45 a frame comprising stationary side members having relatively narrow, integral, projecting portions, a material-supporting member supported by said projecting portions and having a turning movement relatively thereto, a member of substantially U-shape having 50 one end portion secured to said material supporting member, and a metal cap member secured to and interlocked with the other end portion of said member of U-shape, the intermediate portion of said member of U-shape being located outside of said projecting portion whereby a turning movement of

the material-supporting member may be effected by said metal cap member.

4. In a vertical toaster, in combination, a frame comprising stationary side members 60 having relatively narrow, integral, projecting portions, a material-supporting member supported by said projecting portions and having a turning movement relatively thereto, a member of substantially U-shape 65 having one end portion secured to said material supporting member, and a metal cap member secured to and interlocked with the other end portion of said member of U-shape, the intermediate portion of said member of U-shape being located outside of 70 said projecting portion and co-operating with said side member to limit the turning movement of said material-supporting member in one direction.

5. In a vertical toaster, in combination, a frame comprising a stationary sheet metal side member having a relatively narrow, integral portion projecting laterally of said member in the plane thereof, a material-carrying tray pivotally supported by the projecting portion of said side member, a thin metal member of substantially U-shape having one end secured to said tray, the other end being of substantially hexagonal 85 contour, and an operating button, having an inner depression adapted to receive said end of substantially hexagonal contour, for actuating said tray.

6. In a vertical toaster, in combination, a frame comprising a stationary, sheet metal side member having a relatively narrow, integral portion projecting laterally of said member in the plane thereof, a material-carrying tray pivotally supported by the projecting portion of said side member, a thin metal member of substantially U-shape having one end secured to said tray, the other end being of substantially hexagonal contour, and an operating button, having an inner depression adapted to receive said end of substantially hexagonal contour, for actuating said tray, the intermediate portion of said member of U-shape co-operating with said side member to limit the turning movement of said tray in one direction.

In testimony whereof, we have hereunto subscribed our names this 7th day of May, 1923.

ORA A. COLBY.
CHRISTIAN AALBORG.
